UNITED STATES PATENT OFFICE

98,454

DESIGN FOR A MANICURIST KIT

Eleanor Conradsen, Los Angeles, Calif.

Application May 17, 1933, Serial No. 48,152

Term of patent 7 years

To all whom it may concern:

Be it known that I, Eleanor Conradsen, a citizen of the United States, residing at Los Angeles, in the county of Los Angeles, and State of California, have invented a new, original, and ornamental Design for a Manicurist Kit, of which the following is a specification, reference being had to the accompanying drawings, forming a part thereof.

Figure 1 is a top plan view of a manicurist kit, showing my new design and with the covers in closed position.

Fig. 2 is a front elevational view of the manicurist kit shown in Fig. 1.

Fig. 3 is an end elevational view of the manicurist kit shown in Fig. 4 and with some of the covers moved to opened position as seen in Fig. 4.

Fig. 4 is a top plan view of a manicurist kit showing my new design and with the drawers partly opened and some of the covers moved to open position.

Fig. 5 is a perspective view of a manicurist kit, showing my new design with the drawers partly opened and some of the covers moved to open position.

I claim:

The ornamental design for a manicurist kit, as shown and described.

Signed at Los Angeles, in the county of Los Angeles, and State of California, this 11th day of May, 1933.

ELEANOR CONRADSEN.
